UNITED STATES PATENT OFFICE.

JOHN W. BOWERBANK, OF LOS ANGELES, CALIFORNIA.

RADIATOR FOR AUTOMOBILES.

1,079,468.

Specification of Letters Patent.

Patented Nov. 25, 1913.

Application filed September 16, 1912. Serial No. 720,681.

To all whom it may concern:

Be it known that I, JOHN W. BOWERBANK, a citizen of the United States, residing at Los Angeles, in the county of Los Angeles and State of California, have invented a new and useful Improvement in Radiators for Automobiles, of which the following is a specification.

This invention relates to radiators, and especially to radiators designed for automobiles, and the principal object is to provide a radiator in which the full area of the metal in contact with the water will be exposed to the air currents.

It is also an object to provide a radiator in which the component elements can be readily separated and quickly assembled, the junction of the flanged sides of a pair of component elements being joined to form a tubular structure with an air space intervening between the tubular fluid bearing passages.

It is a further object to provide a radiator, a section of which can be readily removed without taking down the whole structure to make repairs to an individual element.

In the drawings accompanying this specification and forming therewith the application for Letters Patent: Figure 1 is a front elevation of a radiator of the usual automobile form, showing my invention as applied thereto. Fig. 2 is a central longitudinal section through a pair of the component units, clearly showing the method of forming the latter with their fins. Fig. 3 is a cross section on the line 3—3 of Fig. 1, clearly showing the junction of the flanges.

Heretofore in the building of radiators tubular structures have been used, the terminal ends of which have been inserted into slotted plates secured to the housing, resulting in a structure difficult to repair, inefficient in its operation and easily clogged, thus preventing free circulation and necessitating the taking down of the entire structure to repair damages sustained in a small portion of the structure.

This invention overcomes the difficulties above referred to in that it provides a tubular structure formed by the joining of a plurality of units by simple means, which are easily separated by the application of heat and a section removed readily from the radiator, doing away entirely with the terminal plates.

More specifically in the drawings like nu-

merals indicate the same parts in the different views, 5 representing the housing of an automobile radiator, provided with the usual inlet opening 18 and outlet 17 entering the proper chambers, the exterior casing of the radiator has not been shown. Supported in the housing are a plurality of component units 6, which, joined in their proper relation and secured in the housing as herein-after described, constitute the improved radiator. A suitable pump, not shown, forces the water through the radiator and the water jackets of the motor.

The cross section of the housing as clearly shown in Fig. 3, consists of a U shaped structure provided with the preferably inturned flanges 7, or the edges may be terminated in the same plane as the body of the structure, as is clearly shown in the broken away portion of Fig. 1, these edges overlapping the component members of the core.

More particularly the core is formed by the securing together of a series of core units preferably formed as shown in Fig. 2 of a continuous strip of copper, or other good conductor of heat, in the general elongated rectangular form, the edges of the strip being turned to form the external flanges 8, the faces of these flanges being parallel with the surface of the strip. The thickness of these units is determined by dividing the area to be covered by the number of elements desired, the upper end is formed in the middle of the strip by turning the sides down and carrying them parallel to the base where they are double seamed at 9 and securely soldered in any well known manner. The space inclosed by the inner surfaces of the copper strips forming a core unit is filled by the fin 10 preferably formed, as shown, of a fluted or corrugated strip of metal doubled on its edges. The width of the fin being preferably slightly less than that of the core unit. The fins are also formed of one continuous strip bent to form the loop 12 at the upper point, the lower edge being flanged and rolled to a tight fit as shown at 13. These are slidably mounted in the core member and secured in the final operation of assembling the complete core. A similar core member is placed adjacent to the one already described and a series of them placed side by side with the fins therein are dipped into a dipping pan until the solder flows to the inner edges of the flanges, thus securely

binding the whole and forming a series of the tubular liquid passages 15. As will readily be seen the water or other contained fluid in this passage way comes in contact 5 with the entire metallic surface, the solder not interfering with any of the radiating area and the fins being in close contact with the exterior surface of the tubular passage ways providing a maximum amount of radiating surface for the structure. The whole core is now placed in position in the housing, a stream of solder closes up the one continuous joint around the points of contact of the core with the housing, resulting in a simple and readily assembled structure.

The side walls of the housing are preferably provided with the plates 16 spaced inside the flanges so that the same area of 20 water will be carried in the tubular passage 15 between the core unit 6 adjacent to the housing and the plate 16.

As will be seen there is only one short seam in the core unit, and the interior of the 25 passage way is perfectly smooth and readily opened by softening the solder along its longitudinal seam on either side when one section can be slipped out without damage or interference to the others, resulting in a 30 great saving of labor in assembling the structure and the amount of solder used is reduced about one-fourth.

This structure will not break in freezing, as sufficient elasticity is present to provide 35 for the expansion as the water is converted into a solid state, and danger from steam pressure is also lessened in view of the expandible qualities.

What I claim is:

40 1. In a radiator construction, a core unit

formed of an integral strip of sheet metal, comprising two side walls and two end walls, the edges of said walls being bent upon themselves to form channels continuous with their external faces, said channels 45 being so formed that they open toward one another on the same side wall, so said unit may be joined by said inturned edges to a unit of the same construction, whereby 50 internally disposed radiating web parallel with the side walls of the respective units.

2. In a radiator construction, a radiator core formed of a strip of sheet metal having its lateral edges bent upon themselves to 55 form channels adjacent said edges with the side walls of said channel in parallel relation, said channeled strip being bent to form side walls and end walls with the channels externally thereof, the terminal ends of said 60 strip being lock joined at one of said end walls, to form an elongated rectangular structure whereby the parallel externally 65 channeled faces of a plurality of units may be joined along said outer side walls of said channels to form an expandible fluid passage of elongated cross section having a longitudinal web intermediate of its side walls and extending centrally into said fluid passage, and means to secure said walls whereby 70 no radiating area is lost and one unit may be readily separated from a plurality of units so joined.

In witness that I claim the foregoing I have hereunto subscribed my name this 5th 75 day of Sept., 1912.

JOHN W. BOWERBANK.
